(57) **CLAIM**

The ornamental design for a surgical microscope as shown and described.

DESCRIPTION

FIG. 1 is a front elevational view of a first embodiment of a surgical microscope showing our new design;

FIG. 2 is a rear elevational view thereof;

FIG. 3 is a right side elevational view thereof;

FIG. 4 is a left side elevational view thereof;

FIG. 5 is a top plan view thereof; and

FIG. 6 is a bottom plan view thereof.

FIG. 7 is a front elevational detail view thereof showing a portion indicated by lines 7-7 on FIGS. 1 and 3;

FIG. 8 is a front, bottom, left perspective detail view thereof showing a portion indicated by lines 8-8 on FIG. 3;

FIG. 9 is a rear, bottom, right perspective detail view thereof showing a portion indicated by lines 9-9 on FIG. 3;

FIG. 10 is an enlarged front elevational detail view thereof along the lines 10-10 and 10'-10' of FIG. 7;

FIG. 11 is an enlarged front, bottom, left perspective detail view thereof along the lines 11-11 and 11'-11' of FIG. 8; and

FIG. 12 is an enlarged rear, bottom, right perspective detail view thereof along the lines 12-12 and 12'-12' of FIG. 9;

FIG. 13 is a front elevational view of a second embodiment of a surgical microscope showing our new design;

FIG. 14 is a rear elevational view thereof;

FIG. 15 is a right side elevational view thereof;

FIG. 16 is a left side elevational view thereof;

FIG. 17 is a top plan view thereof; and

FIG. 18 is a bottom plan view thereof.

(Continued)

FIG. 19 is a front elevational detail view thereof showing a portion indicated by lines 19-19 of FIGS. 13 and 15; FIG. 20 is a front, bottom, left perspective detail view thereof showing a portion indicated by lines 20-20 of FIG. 15; FIG. 21 is a rear, bottom, right perspective detail view thereof showing a portion indicated by lines 21-21 of FIG. 15; FIG. 22 is an enlarged front elevational detail view thereof along the lines 22-22 and 22'-22' of FIG. 19; FIG. 23 is an enlarged front, bottom, left perspective detail view thereof along the lines 23-23 and 23'-23' of FIG. 20; and, FIG. 24 is an enlarged rear, bottom, right perspective detail view thereof along the lines 24-24 and 24'-24' of FIG. 21. The even-dash broken lines show portions of the surgical microscope and form no part of the claimed design. The dot-dash broken lines define the boundaries of the claimed design and form no part thereof.
